UNITED STATES PATENT OFFICE.

JAMES GRANT, OF COBRAM, VICTORIA, AUSTRALIA.

DISK CULTIVATOR.

No. 853,510.

Specification of Letters Patent.

Patented May 14, 1907.

Application filed August 8, 1906. Serial No. 329,796.

To all whom it may concern:

Be it known that I, JAMES GRANT, a subject of the King of Great Britain and Ireland, residing at Queen street, Cobram, in the county of Moira, State of Victoria, Commonwealth of Australia, engineer, have invented certain new and useful Improvements in Disk Cultivators, of which the following is a specification.

10 My invention relates to disk cultivators and its object is to provide an implement which shall not only be cheap in first cost but also effective and convenient in use. Among its chief features are:—The right and left hand sides of the frame can be elevated or depressed by hand levers, the back of the frame can also be elevated or depressed by shifting collars, the disk shaft can, one end at a time, or both ends together, be elevated or lowered in relation to the frame, the front end of the said disks can likewise be moved backward or forward and thereby be inclined to the angle of draft and a thrust bracket is provided which is capable of moving along the left hand frame piece, and has a thrust block therein which is adjustable.

Referring to the drawings which form a part of this specification Figure 1 is a plan of my invention. A small portion of the diagonal frame piece is broken away and one clamp removed to illustrate one of the disk shaft bearings and lug thereon. Fig. 2 is a view, on a reduced scale, of my cultivator looking at it from the left hand side. Fig. 3 is a perspective view, on an enlarged scale of the furrow wheel and the means whereby it is moved outwardly or inwardly, elevated or depressed, and inclined to the line of draft. Fig. 4 is an elevation on an enlarged scale of the thrust bearing bracket. Fig. 5 is a sectional elevation of Fig. 4. Fig. 6 is a detail view on an enlarged scale of a disk shaft bearing and the means for elevating, depressing, or inclining the disks.

45 Similar letters of reference indicate similar or corresponding parts where they occur in the several views.

My invention includes a frame in which is a left hand frame piece A (Figs. 1 and 2). Also a front frame piece B. On the right hand end of the said front frame piece is a forward extension frame piece C. Behind the forward extension frame piece C is an adjusting backward extension frame piece D (Fig. 1). The length of this will depend upon circumstances. From the back end of

D to the frame piece A extends a diagonal frame piece E. To the diagonal frame piece E and to the foot F on the left hand frame piece A is attached a supplementary frame piece G. Between the front frame piece B and diagonal frame piece E is a cross frame piece H.

To the supplementary frame piece G and the foot F is attached a bearing J (Figs. 1 and 2) having therein a vertical hole. Adjacent to the said bearing is a stop plate K. Through this stop plate are adjusting holes L (Fig. 1) into which passes a stop pin M secured by a chain or other means to the frame. Into the vertical hole in the bearing passes a vertical portion on the inner end of a stem or wheel carrying arm N. Above and below the bearing J and around the said vertical portion are shifting collars O whereby the said vertical portion may be locked vertically in any desired position in the bearing J. On the outer end of the wheel carrying arm N turns the back wheel P. By means of the stop pin M the back wheel P may be retained at any particular angle with the line of draft.

Near the front left hand side of the machine is the land wheel Q. The said land wheel turns upon the outer end of a stud R, the inner end of which is secured to the outer end of the short arm S (see Fig. 2) of a bell crank lever. The angle of the said bell crank lever turns upon the overhanging end of a shaft T. (Figs. 1 and 2). The long arm or land wheel hand lever U extends to near the operator's seat and is locked in any desired position vertically by a pawl V engaging in a notched quadrant W. The said notched quadrant is attached to the frame in any well known way.

To the forward extension frame piece C is attached (see Figs. 1, 2 and 3) a bracket X. In this are holes to accommodate the sliding bar Y. This bar is locked by locking screws Z and is capable of moving endwise to or from the implement. Integral with the outer end of said sliding bar Y or attached thereto is a bearing A¹. In this is a vertical hole. Attached to or integral with the bearing and the sliding bar Y is a forward arm B¹. Extending backwardly is a backward arm C¹. To this backward arm is attached a notched rack D¹.

To the forward arm B¹ is pivoted at E¹ the lower end of the furrow wheel lever F¹. The upper end of the said furrow wheel lever is

close to the driver and the said lever is locked in any desired position by a pawl G^1 engaging with the notched rack D^1 . To the furrow wheel lever F^1 by a pivot pin H^1 (see Fig. 3) are pivoted the lower ends of two links J^1 . The upper ends of the said links by a pivot pin K^1 are pivoted to the vertical member L^1 of an elbow piece. The horizontal member M^1 has a hole therethrough to accommodate the stem N^1 . Near the upper end of the said stem N^1 and attached to it is the inner end of a steering lever O^1 . To the outer end of the steering lever O^1 is pivoted by a pivot pin P^1 the steering handle Q^1 . The back end of the said steering handle Q^1 drops into the grooves within a notched bar O^3 . The intermediate portion of the stem N^1 passes through the bearing A^1 and the lower portion of it is bent outwardly and upon it turns the furrow wheel R^1 capable of being moved sideward. The upper end of the said stem passes through the horizontal member M^1 of an elbow piece and above it is a nut and washer.

Below the diagonal frame piece E is situated the disk shaft S^1 . Upon this and turning with it are any number of disks T^1 . The said shaft turns in a back and front bearing U^1 (see Figs. 1 and 6). Each of these has above it a lug V^1 . Through each lug is a hole to accommodate freely a bolt W^1 (see Fig. 6). These bolts pass through the forked legs X^1 , situated at the bottom of a bearing holding rod Y^1 (removed from one side of Fig. 1 for convenience of illustration). The said bearing holding rods pass through holes in the arms Z^1 of a clamp. The back A^2 of the said clamp has a locking screw B^2 therein. The front clamp is capable of moving along the adjusting backward extension frame piece D so that the front end of the disks may be moved backward or forward, and locked in any desired position. On the supplementary frame piece G is supported a driver's seat C^2 and foot rests D^2 (see Fig. 1). To the front frame piece B is attached the draft bar E^2 in which are a series of holes to permit adjustment of the draft chain F^2 . At the back end of the said disk shaft S^1 and supported from the left hand frame piece A is placed a thrust bearing bracket G^2 . This is capable of moving backward or forward upon the said frame. In the bottom of said bracket (see Fig. 5) is a chamber H^2 , in which is a thrust block J^2 . In the top of this thrust block may be an oil well K^2 which by a channelway communicates with the thrust hole L^2 . An oil hole M^2 in the bracket assists the passage of a lubricant to the thrust block J^2 . Behind the thrust block J^2 is an adjusting screw N^2 . Or instead of the said thrust bearing bracket being attached to the frame piece A it may be attached to a cross piece thereon at right angles to the disk shaft when in its normal position.

65 The cycle of operations with my invention

is as follows.—The driver on the seat C^2 when starting out from the farm and passing over a common road depresses the lever U and the lever F^1 . They lock themselves by the pawls springing into a notch in the quadrant. He also raises the rear end of the frame by moving the shifting collars O on the vertical portion of the stem N carrying the back wheel P . The disks are then above the road and in safety and he steers by means of the steering handle Q^1 . Having arrived at the scene of operations he elevates the aforesaid levers and moves the shifting collars O and the frame falls and with it descend the disk shaft and the disks. Should, however, the adjustment between the frame and the disks be unsuitable the relative position of the disks and the frame can be adjusted by the clamp screws B^2 . These permit the bearing holding rods Y^1 to slide upwardly or downwardly within the arms Z^1 . By slackening the locking screw B^2 on the front clamp the front end of the disk shaft may be moved backward or forward. When the front disk shaft bearing is attached to the lower member of an L piece the range of its backward and forward adjustment may be increased.

Having now described my invention what I claim as new and desire to secure by Letters Patent is.—

1. In a disk cultivator the combination with a frame having a backward extension frame piece, a left hand frame piece, and a diagonal frame piece; of a disk shaft below said frame, bearing holding rods supporting the shaft, clamps engaging the backward extension piece and the diagonal frame piece, said clamps adjustably engaging the rods, a thrust bearing bracket connected to the left hand frame piece and adjustable thereon, and a thrust block adjustably mounted within said bracket and constituting an end bearing for the shaft.
2. In a disk cultivator the combination with a portable frame, and means for adjusting said frame vertically; of a diagonally arranged shaft within the frame, adjustable means for supporting said shaft from the frame, means for adjusting said shaft longitudinally, and disks carried by the shaft.
3. In a disk cultivator the combination with a portable frame; of a diagonally arranged shaft, vertically and laterally adjustable means for supporting the shaft from the frame, a bracket secured to the frame, a thrust block constituting an end bearing for the shaft, means for adjusting said block to shift the shaft longitudinally, and disks upon the shaft.
4. In a disk cultivator the combination with a portable frame; of a diagonally-disposed shaft extending throughout the width of the frame, disks upon the shaft, adjustable

means for supporting the shaft at points between its ends, and means for imparting longitudinal movement to said shaft.

5. In a disk cultivator the combination with a portable frame; of a diagonally arranged shaft extending throughout the width of the frame, disks upon the shaft, longitudinally and vertically adjustable supports for the shaft and mounted on the

frame, and means for imparting longitudinal movement to the shaft.

In testimony whereof I affix my signature in the presence of two subscribing witnesses:

JAMES GRANT.
